UNITED STATES PATENT OFFICE.

LOUIS D. LAWNIN, OF EDWARDSVILLE, ILLINOIS, ASSIGNOR OF ONE-HALF TO N. O. NELSON
MANUFACTURING COMPANY, OF ST. LOUIS, MISSOURI, A CORPORATION OF MISSOURI.

FLUSHING DEVICE FOR WATER-CLOSETS.

No. 800,176.

Specification of Letters Patent.

Patented Oct. 6, 1908.

Application filed June 24, 1907. Serial No. 380,518.

To all whom it may concern:

Be it known that I, LOUIS D. LAWNIN, a citizen of the United States of America, and a resident of the city of Edwardsville, in the county of Madison and State of Illinois, have invented certain new and useful Improvements in Flushing Devices for Water-Closets, of which the following is a full, clear, and exact description, reference being had to the accompanying drawings, forming part of this specification.

My invention relates to a flushing device for water closets that is arranged to be operated by an arm which depends from the hinged seat of the closet bowl when the seat is depressed so as to move a valve rearward, for the purpose of admitting water to the flushing tank and to be operated by the force of water delivered from the flushing tank to the bowl when the seat is released which moves the valve forward, in order that the bowl may be flushed while the flow of water to the tank is discontinued.

My invention has for its object the production of a simple and efficient flushing device of this character, in which the parts are so constructed that the entire valve stem and its valves may be withdrawn from the valve shell at its forward end, when there is occasion for such withdrawal, without any necessity of detaching the valve shell from the closet bowl and its other connections.

A further object of my invention is to provide a relief vent between the chamber in which the supply controlling valve operates and the water supply connection, for the purpose of obviating the occurrence of cushioning action at the rear of said valve when the closet seat is occupied, and permitting ready movement of the valve and the stem by which it is carried when the seat is depressed.

Figure I is in part an elevation, and in part a vertical section of a water closet in which my flushing device is utilized. Fig. II is an enlarged vertical section taken through the flushing device and the rim of the closet bowl, and a fragment of the seat associated with said bowl. Fig. III is a vertical cross section taken on line III—III, Fig. II. Fig. IV is a vertical cross section taken on line IV—IV, Fig. II.

In the accompanying drawings, A designates a water closet bowl having a rim B containing a channel C. In the outer wall

of said rim is an aperture D, and in the inner wall of said rim is an aperture E, said apertures being designed to receive portions of the valve device to be hereinafter described.

F is a closet seat that is hinged to a suitable support and surmounts the bowl A, and from which depends an arm G having a utility that will be hereinafter set forth.

H is a water supply pipe.

I is a flushing tank adapted to receive a supply of water and which is closed to prevent the escape of water therefrom, in order that when water is admitted to the tank the air present therein will be compressed.

J is a flushing pipe leading to the flushing tank. The parts thus far described are known to be old and no invention *per se* is herein claimed for them.

1 designates the shell of my valve device which is attached to the rim of the bowl A and is interposed between the water supply pipe H and the flushing pipe J. This valve shell is provided at its forward end with a nipple 2 which extends across the outer wall and enters into the channel of the rim of the bowl A and terminates in a reduced neck 3 located within the channel and containing radial perforations 4 for the escape of water from the interior of the valve shell to the channel in the bowl rim as will hereinafter appear. It will be observed that the alined apertures D and E in the rim of the bowl are approximately of the same diameter.

5 is a bushing that extends across the channel of and is seated in the apertures D and E of the walls of the bowl rim, and which extends over the reduced neck 3 and receives and is secured to the nipple 2 of the valve shell, as seen in Fig. II. This bushing is provided with radial apertures 6, through which the water that passes through the perforations in the neck of the nipple 2 may find escape to the channel in the bowl rim. At the interior of the bushing 5, and near its forward end, is an apertured diaphragm 7 in which the aperture is of sufficient diameter to permit of the withdrawal of the valve stem of my device and its appendages forwardly through said diaphragm and into the bowl, as will hereinafter appear.

8 is a nut that is fitted in the forward end of the bushing 5 and serves to close this end

of the bushing. The nut is provided with a central aperture 9 that receives the forward end of the valve stem, to be presently more particularly referred to.

5 10 is a cup leather that is seated between the nut 8 and the diaphragm 7. At the rear end of the valve shell 1 is a tubular arm 1' that is closed at its rear end by a nut 11 having an internal guide-way 12. At the 10 lower side of the tubular arm of the valve shell is a depending nipple 1^a, to which the water supply pipe H is connected, and at the junction of said depending nipple and the body of the shell is a perforated dia- 15 phragm 1^b.

1^c is a tubular horn that projects upwardly from the body of the valve shell, and to which the flushing pipe J is connected.

13 designates the valve stem of my device 20 operable in the valve shell 1, and which carries a forward valve 14 movable in the nipple 2 and its neck 3 and a rear valve 15 that is movable in the tubular arm 1' of the valve shell. The first mentioned forward valve 25 serves to control flow of water from the chamber of the valve shell to the channel in the rim of the bowl A, and the other or rear valve serves to control the flow of water from the supply pipe to the valve shell 30 chamber. The valve stem has a forward extension 13' that is operable through the cup leather 10 and the nut 8 in the bushing 5, and in the recessed end of which is seated an anti-friction ball or a roller 16 which 35 receives the engagement of the depending arm G, carried by the seat F of the water closet. The valve stem also has a rear extension or guide member 13^a that is operable in the guide-way in the rear nut 11, and is 40 preferably surrounded by an expansion spring 17, which is of service in returning the valve stem in a forward direction in the event of the pressure of the flush water directed against the valve 14, which is larger 45 than the rear valve 15, being insufficient to move the valve stem forwardly, after it has been operated through the medium of the water closet seat.

18 designates a relief vent duct or by-pass, 50 leading from the chamber in the rear tubular arm 1' of the valve shell to the depending nipple 1^a, that has connected to it the water supply pipe H. This relief vent duct is of very material service in my valve device in permitting the escape of water from the chamber in said valve shell arm at the 55 rear of the valve 15, for the purpose of avoiding the occurrence of a water cushion at the rear of said valve, which would render it difficult for the valve stem to be moved upon its receding stroke under the action of the water closet seat when said seat is depressed. By providing the relief vent duct, the air and any water that may 60 have entered into the chamber in the tubu- 65 lar arm 1' back of the valve 13, readily escapes from said chamber as the valve moves rearwardly and is forced into the water supply connections.

In the practical use of my valve device, 70 the operation is as follows: When the parts of the valve device are in the position shown in Fig. II, the flushing tank is filled with water which is under water column and air pressure, due to the compression of air in the 75 tank above the water. When the parts are as shown, it is to be assumed that the seat is in a depressed position and occupied. Then, when the seat is relieved of restraint, the water is forced from the flushing tank 80 through the flushing pipe and exerts its force against the forward valve 14 which, as previously stated, is larger than the rear valve 15, thereby causing the valves 14 and 15 to be carried with the valve stem 13 to 85 the positions indicated in vertical dotted lines Fig. II. The forward valve being at this time carried to a position in front of the perforations in the nipple neck 3, the flush water readily passes through said perforations and then through the perforations 6 in the bushing 5 and enters the channel in the rim of the water closet bowl to escape therefrom into the interior of the bowl for flushing action. Upon the water closet seat being 90 again depressed, its arm G acts against the forward extension of the valve stem with the result of forcing said stem rearwardly together with the valves carried by it. As the rear valve 15 moves rearwardly, the perforated diaphragm 1^b at the top of the depending nipple 1^a of the valve shell is uncovered and a supply of water is permitted to pass from the supply pipe H into the chamber of the valve shell and flow therefrom upwardly 105 to the flushing tank for the purpose of replenishing the supply therein for service in the same manner as that previously described when the water closet seat is freed from restraint.

I desire to direct particular attention to the fact that the opening in the valve stem incasing members of my valve device fitted to the rim of the water closet bowl is of such dimensions as to be equal to or greater than 110 the transverse dimensions of any part of the valve stem or the valves and their appurtenances carried by the stem and consequently when the nut 8 which closes the foremost valve stem incasing member is removed, the 115 stem of the valve and all of its appurtenances may be readily withdrawn into the water closet bowl without the necessity of making disconnections of the valve casing from the bowl or from the water conducting 120 pipes attached to such casing. I thus provide for the removal of the valve stem and its valves with a minimum of labor whenever it is necessary to make repairs in such parts or to substitute new parts for those 130

which have become unfit for further use and avoid all injury to the valve casing and its connections which frequently occurs in valve devices of like character that must be separated from their connections previous to the removal of the valves and valve stems for repairs or renewal of parts.

Claim:

10 A flushing device comprising a valve shell formed with a hollow horn, a tubular arm having a supply pipe nipple, and a by-pass between the tubular arm and the supply pipe nipple, and a nipple having a reduced neck

provided with a radial perforation, a housing having an apertured diaphragm, and 15 extending over the reduced neck and receiving the nipple of the valve shell, a nut closing the aperture in the diaphragm, a valve stem operable in the valve shell and its tubular arm, and valves carried by the valve 20 stem.

LOUIS D. LAWNIN.
